United States Patent Office

Des. 187,834
Patented May 3, 1960

187,834

DISPLAY RACK

Georges Tirlet, Calvados, France, assignor to Etablissements G. Tirlet, Saint-Germain-de-Livet (Calvados), France

Application July 9, 1958, Serial No. 51,718

Claims priority, application France May 17, 1958

Term of patent 3½ years

(Cl. D80—10)

Fig. 1 is a perspective view of a display rack, showing my new design; and

Fig. 2 is a side elevational view thereof on a reduced scale.

I claim:

The ornamental design for a display rack, substantially as shown.
